UNITED STATES PATENT OFFICE.

CHARLES H. CROMWELL, OF GEORGETOWN, ILLINOIS.

BED-HINGE FOR AUTOMOBILE-TRUCKS.

1,396,678.

Specification of Letters Patent. Patented Nov. 8, 1921.

Application filed May 12, 1921. Serial No. 468,992.

To all whom it may concern:

Be it known that I, CHARLES H. CROMWELL, a citizen of the United States of America, and resident of Georgetown, in the county of Vermilion and State of Illinois, have invented certain new and useful Improvements in Bed-Hinges for Automobile-Trucks, of which the following is a specification.

10 This invention relates to hinges for mounting a dumping bed on a Ford truck, the said invention having for its object the provision of an element adapted to be connected to the bed, and an element adapted to be connected to the chassis frame, including means whereby one member is hingedly connected to another, it being understood that two complete hinges are employed for each truck.

20 An object of this invention is to provide a hinge member adapted to embrace the sill of a body and adapted also to be attached to the said sill, associated with a member adapted to be connected to the chassis frame in a manner to be securely retained, in order that it will withstand shock, due to the dumping of the body or bed and to the vibration incident to the use of the body when loaded.

30 An object of this invention also is to provide means whereby the member attached to the chassis frame may be provided with two points of anchorage, while at the same time, the members may be in such spaced relation to each other as to cause them to register with the sills of the bed for connection to the hinge members carried by the said sills.

40 A further object of this invention is to produce a hinge member for the chassis frame which may be of comparatively light material, but so formed as to have great rigidity and strength.

45 With the foregoing and other objects in view, the invention consists in the details of construction, and in the arrangement and combination of parts to be hereinafter more fully set forth and claimed.

50 In describing the invention in detail, reference will be had to the accompanying drawings forming part of this application wherein like characters denote corresponding parts in the several views, and in which—

55 Figure 1 illustrates a view in elevation of

a fragment of a chassis frame and bed, with the hinge embodying the invention applied thereto;

Fig. 2 illustrates a sectional view on the line 2—2 of Fig. 1; 60

Fig. 3 illustrates a perspective view of one of the hinge members; and

Fig. 4 illustrates a perspective view of the coacting hinge member.

In these drawings 5 denotes the hinge member adapted to be attached to a chassis frame, and as shown, this member comprises a plate or main body portion having an angularly disposed extension 6. The hinge member is flanged at its edges as shown at 70 7 and 8, in order to increase the strength of the structure, and the said body has a transversely disposed rib 9 with apertures 10. The hinge member 5 is applied to the end rail 11 of the chassis frame with the rib 9 in 75 contact with the said rail. Fastenings 12 extend through the rail and through the rib, whereby the hinge member is attached to the said rail. The angularly disposed extension has apertures such as 13, and this 80 angularly disposed portion overlies a side member 14 of the frame and it is secured thereto by fastenings 15. The hinge member terminates in a hinge butt 16 which receives a pin 17 to connect the hinge member 85 5 to the coacting hinge member 18. By the arrangement indicated, the hinge butt is held in position under the body sill 19, whereas the plate may be attached to the end rail and anchored to the side member 14 90 of the frame, by reason of the angularly disposed extension 6, and this results in a 95 durable and strong connection and structure.

The companion hinge element 18 comprises a plate having apertured ears 20 to receive the pin 17, and the said plate has parallel flanges 21 and 22 which embrace the sides of the sill, and the said flanges are secured to the sill by fastenings such as 23. 100 The plate of the hinge member 18 also has apertures 24 to receive the fastenings 25 anchored to the sill through the under side thereof. The hinge butt 16 lies between the ears, as shown, and the hinge member 18 is 105 free to swing rearwardly. The joint between the hinge member 5 and the hinge member 18 is such as to leave very little lost motion between the upper side of the hinge member 5 and the lower side of the hinge member 110.

18, in fact, they are in contact, so that the hinge members, rather than the pintles, support the load.

It will be seen from an inspection of the drawing that the hinge member 5 can be made almost wholly by the stamping process, a condition which results in an inexpensive production, whereas the other hinge member is likewise comparatively simple and may 10 be expeditiously applied or installed.

While I have indicated that the invention is particularly adaptable for attachment to Ford trucks, yet it can be applied with the same advantage to other trucks for automobiles, and I do not wish to be limited in this 15 respect in the claim.

I claim:

1. In a bed hinge for automobile trucks, a plate having a rib on its under surface 20 adapted to contact an end rail of a chassis frame, the said plate having an angularly disposed extension adapted to overlie and be secured to a side of the frame, a hinge butt

formed on the outer end of the said plate, a hinge member having flanges adapted to 25 embrace the sides of a body sill and having ears embracing the ends of the hinge butt, and a pivotal pin extending through the said hinge butt and through the ears.

2. In a bed hinge for automobile trucks, a 30 plate having marginal flanges, a hinge butt and a rib transversely of the plate between the marginal flanges near the hinge butt, an extension of the said plate standing at an angle thereto and adapted to engage a side 35 member of a frame, means for anchoring the plate and the extension thereof to a chassis frame, and a hinge member comprising a plate having flanges for embracing a sill of a body, the said plate having depending ears 40 provided with apertures, the said ears being adapted to embrace the ends of the hinge butt, and a pivot extending through the said ears and through the said hinge butt.

CHARLES H. CROMWELL.
